COLLATING MACHINE

David E. Fornell, Detroit, Mich.

Application December 11, 1952, Serial No. 22,645

Term of patent 14 years

(Cl. D64—11)

To all whom it may concern:

Be it known that I, David E. Fornell, a citizen of the United States, residing at Detroit, State of Michigan, have invented a new, original, and ornamental Design for a Collating Machine, of which the following is a specification, reference being had to the accompanying drawing, forming a part hereof.

Fig. 1 is a front oblique view of a collating machine embodying my new design; and

Fig. 2 is a rear oblique view of a collating machine embodying my new design.

The characteristic features of my design reside in the portions shown by means of full lines in the drawing.

I claim:

The ornamental design for a collating machine, as shown and described.

DAVID E. FORNELL.
